UNITED STATES PATENT OFFICE.

ALBERT B. CHANCE, OF CENTRALIA, MISSOURI.

ANCHOR.

1,384,825.

Specification of Letters Patent. Patented July 19, 1921.

Application filed July 26, 1917. Serial No. 182,947.

To all whom it may concern:

Be it known that I, ALBERT B. CHANCE, a citizen of the United States of America, residing at Centralia, in the county of Boone and State of Missouri, have invented a new and useful Anchor, of which the following is a specification, reference being had to the accompanying drawings, illustrating the preferred form of the invention.

10 My invention relates to land anchors, used for various purposes such as guying telephone and other poles, smoke stacks, etc.

The principal objects of my invention are, to provide improved constructions in land anchors, as herein set forth; to provide an improved anchor rod as herein set forth; and to provide an improved installing and removing tool for the anchor plate, as herein set forth.

20 Other objects will be apparent from the following specification.

In the accompanying drawings illustrating the preferred form of my invention, Figure 1 is a sectional elevation showing the 25 anchor of the invention installed in the earth, the anchor plate being shown in longitudinal cross-section; Fig. 2 is an enlarged view of the anchor plate and rod, taken the same as in Fig. 1, the anchor plate being shown in longitudinal cross-section; Fig. 3 30 is a perspective view of the front side of my improved anchor plate; Fig. 4 is a perspective view of the rear side of my improved anchor plate; Fig. 5 is a transverse cross-sectional view of the anchor plate of Figs. 3 and 4, taken on plane A A of Fig. 3; Fig. 6 is an elevation of my improved anchor rod; and Fig. 7 is an elevation of my improved installing and removing rod or tool.

40 Like characters refer to like parts in the several figures.

In the preferred form of my invention, the anchor plate 1, preferably a malleable iron casting, is provided on the front face thereof 45 with a transverse rib 2, arched as shown at 3, the ends of the arch 3 being extended as longitudinal ribs 4 4 which diverge as shown at 5 5 and extend to the lower end of the plate 1. The upper end of the arch 3 has a 50 rib portion 6 connecting it with the body of the plate 1 for strength. The longitudinal edges of the plate 1 are preferably thickened as at 7 to provide greater strength and rigidity in the plate. The plate 1 is provided with an opening 8 therethrough be-

tween the ribs 5 5 and 4 4 as shown, the portion of the opening between the ribs 4 4 being more in the form of a slot 9 adapted to accommodate the anchor rod. The inner surface of the arched portion 3 is preferably tapered as shown at 10, Fig. 2, so as to accommodate the anchor rod 11 if the plate 1 and rod 11 form an angle with each other less than 90 degrees when coöperating as shown in Fig. 2. When the anchor is installed as shown in Fig. 1, the ribs, 2, 2, 3, 4, 4, 5, 5 and 6 cut into the earth and thereby hold the anchor plate 1 against lateral movement in all directions. The edges 7 7 also cut into the earth and help hold the plate 1 in place.

The rear face of the plate 1 is provided with transverse ribs 12, 13, 13 and 14, and longitudinal ribs 15 15 forming an arch 16 with each other preferably as shown. The 75 ribs 15 15 are also extended as diverging ribs 17 17 to the transverse rib 12. Ribs 18 18, which diverge toward the lower end of the plate 1, extend from the respective transverse ribs 13 13 to the transverse rib 14 80 preferably as shown, these ribs 18 18 in reality being continuations of ribs 5 5 on the opposite side of the plate 1 and sloping toward each other as shown in Fig. 5. Portions of the inner walls of the longitudinal ribs 15 15 are cut away as shown in Fig. 4, to provide inclined surfaces 19 19 down which the head 20 of the anchor rod 11 slides when the anchor is being installed, the head 20 finally resting on the flat ledge 21 formed at the termination of the inclined surfaces 19 19 and arched inside of the arched portion 16 around the end of the slot 9.

All of the ribs provided on the front and rear of the anchor plate 1 give great strength to the plate, besides serving other useful purposes in the installation of the anchor as will be herein more fully described.

The upper end of the anchor plate 1 is 100 provided with a hole 22, a notch 23, and a projection 24, to coöperate with the installing and removing tool shown in Fig. 7, as will be herein more fully described.

The anchor rod 11, preferably an iron 105 rod, is provided with a drop-forged eye 25 at its upper end, and a drop-forged head 20 at its lower end, the eye portion 25 being reinforced on top as shown at 26 to prevent injury thereto in driving the rod 11 into 110

- the earth. The head 20 is pointed at 28 and rounded off at 27 so that the portion 27 forms a ball-and-socket joint with the portion 21 of the anchor plate 1, as shown in Fig. 2, thereby insuring a good bearing between the plate 1 and the head 20 of the rod 11 at whatever angle approximating 90 degrees the plate 1 may be installed relatively to the rod 11.
- 10 The installing tool shown in Fig. 7 comprises a handle portion 29 to the end of which is attached a cast-iron portion 30 having a V-shaped web-portion 31 adapted to fit into the notch 23 in the plate 1 and a projection 32 thereon adapted to enter the hole 22 in the plate 1 for holding the plate 1 while inserting it into the hole in the earth for installing. The plate 1 may be released from the tool 30 by moving the handle 29
- 15 so that the projection 32 is thrown out of the hole 22. The projection 24 on the front side of the plate 1 is for the purpose of preventing the plate 1 from being attached to the tool 30 in a reversed position when being installed, as with the projection 24 the tool 30 must always be engaged against the rear side or underneath side of the plate 1 and not against the front side or top side thereof, when attaching the plate 1 to the tool 30.
- 20 The tool 30 is also provided with a hook 33 thereon to be hooked into the hole 22 in the plate 1 for removing the plate 1 from the hole in the earth when desired.
- 25 The anchor is installed in the earth as follows:

First a hole 34 is bored into the earth at substantially right-angles to the line of strain. Then the anchor rod 11 is driven into the earth to meet the hole 34 as shown in Fig. 1, in substantially the line of strain, the head 20 of the rod 11 extending out into the hole 34. Then the anchor plate 1 is attached to the installing tool 30 as hereinbefore described, the plate 1 being then let down into the hole 34 for engagement with the rod 11 by means of the tool 30. In attaching the plate 1 to the rod 11, the point 28 of the rod 11 may first engage the surface 35 of plate 1 between the ribs 5 5, the converging ribs 5 5 then guiding the point 28 of the rod to and through the opening 8 in the plate 1 as the plate 1 is let down farther into the hole 34 and pressed against the upper wall of the hole 34. From this position the head 20 of the rod 11 slides freely past the upper ends of the converging ribs 18 18 without obstruction and finally slides freely down the inclined surfaces 19 19 to its final position against the surface 21, without obstruction, as the plate 1 is let still farther down into the hole 34, the converging ribs 18 18 guiding the head 20 of the rod 11 onto the inclined surfaces 19 19 which in turn guide the head 20 to its proper position on the arched surface 21. With my improved construction

of the anchor plate 1 as herein set forth, it is impossible for the head 20 of the rod 11 to be retained by the plate at any portion thereof except on the ledge or surface 21. Thus when the anchor is installed I can rest assured that the head 20 of the rod 11 is in its proper position against the ledge 21, forming a ball-and-socket joint therewith. Now the guy strand is attached to the eye 25 of the rod 11, the tool 30 in the meantime removed from the plate 1, and as the guy strand is put under a tensional strain the head 20 of the rod 11 is pulled up firmly against the surface 21 of the plate 1 and the ribs on the front or upper side of the plate 1 bury themselves in the earth as hereinbefore described. Now the hole 34 is tamped full of dirt, which completes the installation of the anchor.

My improved anchor may be installed in various places and under various and difficult conditions, such as on hill sides in various positions where it is impossible to install other anchors.

The design of the anchor rod illustrated in this application, forms the subject-matter of my United States Design Patent No. 56,118, which issued on Aug. 24, 1920, for design for anchor rods.

I do not wish to limit this invention to all of the exact details of construction as herein set forth, as various modifications thereof may be made or utilized without departing from the scope of the appended claims.

What I claim as my invention is:

1. In an anchor of the character set forth, a concavo-convex anchor plate having longitudinal ribs on the convex side thereof connected at one end by an arched rib portion and diverging at the other end toward the corners of one end of the plate, the plate being provided with an aperture therethrough between the said longitudinal ribs and between portions of the said diverging ribs, the said aperture being bordered on the concave side of the plate with longitudinal ribs connected at one end by an arched rib portion and diverging at the other end, the inner walls of the said longitudinal ribs and the said arched rib portion on the concave side of the plate being partially cut away to provide inclined surfaces along the longitudinal ribs terminating in an arched surface within the said arched rib portion on the concave side of the plate, which arched surface lies in a plane substantially parallel with a plane including the longitudinal edges of the plate, the inner wall of the arched rib portion on the convex side of the plate inclining away from the said aperture in the plate, and an anchor rod having a rounded head on one end thereof co-operating with the said ribs and the said arched portions in the installation of the anchor, the said rod extending through the said

- aperture, the said head forming a ball-and-socket connection with the said arched surface within the said arched rib portion on the concave side of the plate, for purposes substantially as set forth.
2. In an anchor of the character set forth, a concavo-convex anchor plate having longitudinal ribs on the convex side thereof diverging at one end, the plate being provided with an aperture therethrough between the said longitudinal ribs and between portions of the said diverging ribs, the said aperture being bordered on the concave side of the plate with longitudinal ribs connected at one end by an arched rib portion and diverging at the other end, the inner walls of the said longitudinal ribs and the said arched rib portion on the concave side of the plate being partially cut away to provide inclined surfaces along the longitudinal ribs terminating in an arched surface within the said arched rib portion on the concave side of the plate, and an anchor rod having a rounded head on one end thereof coöperating with the said ribs and the said arched portions in the installation of the anchor, the said rod extending through the said aperture, the said head forming a ball-and-socket connection with the said arched surface within the said arched rib portion on the concave side of the plate, for purposes substantially as set forth.
3. In an anchor of the character set forth, a concavo-convex anchor plate having longitudinal ribs on the convex side thereof connected at one end by a rib portion and diverging at the other end, the plate being provided with an aperture therethrough between the said longitudinal ribs and between the said diverging rib portions, the said aperture being bordered on the concave side of the plate with longitudinal ribs connected at one end by a rib portion and diverging at the other end, the inner walls of the said longitudinal ribs on the concave side of the plate being provided with inclined portions terminating in a ledge at the narrow end of the said aperture, and an anchor rod having a head thereon coöperating with the said ribs, the said inclined portions and the said ledge in the installation of the anchor, the said rod extending through the said aperture, the said head bearing on the said ledge when the anchor is fully installed, substantially as set forth.
4. In an anchor of the character set forth, an anchor plate having a longitudinally-disposed aperture therethrough widening toward one end of the plate, the said aperture being bordered along the sides thereof on each side of the plate with rib portions, the inner walls of the rib portions on one side of the plate being provided with parallel inclined portions forming an inclined track and terminating in a ledge at the narrow end of the said aperture, and an anchor rod having a head thereon coöperating with the said rib portions the said inclined track and the said ledge in the installation of the anchor, the said rod extending through the said aperture, the said head bearing against the said ledge when the anchor is fully installed.
5. In an anchor of the character set forth, an anchor plate having a longitudinally-disposed aperture therethrough widening toward one end of the plate, rib portions on one side of the plate bordering the sides of the said aperture, the said rib portions being provided with parallel inclined portions forming an inclined track and terminating in a ledge at the narrow end of the said aperture, and an anchor rod having a head thereon coöperating with the said inclined track and the said ledge in the installation of the anchor, the said rod extending through the said aperture, the said head bearing against the said ledge when the anchor is fully installed.
6. In an anchor of the character set forth, an anchor plate having an aperture therethrough, parallel inclined portions on opposite sides of the aperture forming an inclined track and terminating in a ledge at one end of the aperture, and an anchor rod having a head thereon coöperating with the said inclined track and the said ledge in the installation of the anchor, the said rod extending through the said aperture, the said head bearing against the said ledge when the anchor is fully installed.
7. An anchor plate having longitudinal ribs on both sides thereof diverging at one end, the plate being provided with an aperture therethrough between the longitudinal ribs and the diverging portions thereof for accommodating an anchor rod, the longitudinal ribs on one side of the plate being provided with parallel inclined portions along the said aperture forming an inclined track for purposes substantially as set forth.
8. An anchor plate having longitudinal ribs on one side thereof diverging at one end, the plate being provided with an aperture therethrough between the said ribs and the diverging portions thereof for accommodating an anchor rod, the said ribs being provided with parallel inclined portions along the said aperture forming an inclined track for purposes substantially as set forth.
9. An anchor plate having longitudinal ribs on one side thereof, the plate being provided with an aperture therethrough between the said ribs for accommodating an anchor rod, the said ribs being provided with parallel inclined portions along the said aperture forming an inclined track for purposes substantially as set forth.
10. The combination with an anchor rod

having an enlarged end, of an anchor plate having an aperture therethrough and provided with parallel inclined portions along opposite sides of the aperture forming an inclined track for coöoperating with the anchor rod in the installation of the anchor.

As inventor of the foregoing I hereunto

subscribe my name, this 21 day of July, 1917.

ALBERT B. CHANCE.
